UNITED STATES PATENT OFFICE.

LAWRENCE W. MAMMEN, OF CHICAGO, ILLINOIS.

DRIVING MECHANISM FOR WASHING MACHINES.

1,414,430.

Specification of Letters Patent.

Patented May 2, 1922.

Application filed June 18, 1920. Serial No. 389,801.

To all whom it may concern:

Be it known that I, LAWRENCE W. MAMMEN, a citizen of the United States, and a resident of Chicago, in the county of Cook and State of Illinois, have invented a certain new and useful Improvement in Driving Mechanism for Washing Machines, of which the following is a description, reference being had to the accompanying drawing, which forms a part of my specification.

My invention relates to driving mechanism intended more especially for operating power-driven washing machines and has for its object the provision of a construction whereby the direction of rotation or operation of the cylinder or agitator of the washing machine will be automatically controlled and made to operate in reverse directions at predetermined moments; the invention contemplating mechanism which will ensure a positive operation of a shiftable double clutch mechanism in order that the predetermined gear may be brought into operative relation with the driven shaft on the machine; the mechanism being of such construction that the power-transmitting elements may be manually placed in neutral or inoperative position when desired and whereby said power-imparting elements may be manually placed into operative relation in the event of any accidental shifting of said elements during non-use of the machine.

The objects and advantages of my invention will be more readily comprehended from the detailed description of the accompanying drawing, wherein:—

Figure 1 illustrates my improved mechanism, in elevation, with the casing and power-imparting shaft of the machine shown in section and partially broken away.

Figure 2 is a vertical sectional view, taken on the line 2—2 of Figure 1 looking in the direction of the arrows.

My invention, as exemplified in the drawing, discloses the mechanism as adapted to a washing machine in which a suitable agitator or revolving cylinder is intended to be employed. As the cylinder and remaining features of the washing machine proper may be of any of the well known constructions, the same have not been illustrated and further description thereof need not be entered into.

A portion of the power-transmitting shaft is illustrated at 10, leading upwardly from

a motor (not shown) which is adapted to be located at a suitable point on the lower frame members of the machine. The power shaft section 10 extends into a suitable box or housing 11 which is preferably formed integral by means of the hub-portion 12 with the cylindrical shell or housing 13 in which the cylinder-driving mechanism is located. The end of the power shaft section 10, within the housing 11, is provided with a beveled gear 14 which meshes with a beveled gear 15 keyed to a driven shaft 16 which is disposed transversely through the cylindrical portion 13 of the housing or casing. The side of the casing or housing 13, opposite to that provided with the box or housing 11, is provided with a suitable boss-formation 17 adapted to provide proper bearing for the end of the driven shaft 16, while the restricted connection between the portions 11 and 13 of the casing provides bearing for the other end of the shaft 16.

The driven shaft 16 is provided with a pair of beveled pinions 18 and 19 loosely mounted thereon at diametrically opposite points in the casing 13. The rear wall of the casing 13, which is adapted to be secured against the side wall of the tub-portion of the washing machine, is provided with an extension or hub-portion 20, see Figure 2, which is intended to extend through the side wall of the tub or receptacle, a portion of which is indicated at 21, in order to provide proper bearing for the cylinder-supporting and controlling shaft 22, a portion whereof is shown in Figure 2. The end of the shaft 22, disposed within the casing 13, is provided with a circular bevel gear 23 with which the pinions 18 and 19 mesh, but at diametrically opposite points as disclosed in Figure 1.

The shaft 16, at a point intermediate of the bevel gears 18 and 19, is provided with a double clutch member 24 slidably secured to the shaft 16 in any suitable manner, as for example by a slot and pin connection, as shown at 25 in full lines in Figure 2 and in dotted lines in Figure 1, so that the double clutch member 24 is caused to constantly rotate with the driven shaft 16 when the latter is operated by the power shaft section.

The double clutch member 24, at opposite ends thereof, is provided with flanges 26, 26, adapted to be engaged by a sliding member 27.

The member 27 is shown formed in the nature of a two part sleeve adapted to fit about the double clutch member 24; the two members or portions of the sleeve 27 being provided with upwardly disposed flanged portions, as at 28, adapted to be suitably bolted together. The upper surfaces of the flanged portions 28 are kerfed on their adjacent or contacting sides to provide a groove disposed lengthwise of the sleeve, as shown in dotted lines at 29 in Figure 1. This groove 29 is intended to receive a suitable lug 30 formed on the lower surface of a bowed bracket 31 which is secured to lugs formed on the inner surface of the casing 13. With the lug 30 disposed into the groove 29 in the two part sleeve 27, it is evident that the sleeve will be guided in its travel lengthwise of the clutch member 24 and be held against rotation. The lower sides of the sleeve members are also provided with corresponding flanged portions 32, formed so as to provide a space therebetween, to receive an arm or lug 33 formed on a traveling member or nut 34, and permit movement of the arm 33 and therefore of member 34 relative to the sleeve 27. The sides of the flange portions 32 of sleeve 27 are shown provided with elongated slots 35, see Figure 1, into which a pin 36 extends; said pin being disposed through and carried by the arm 33.

The arm or lug 33 is secured and preferably formed integral with the upper part of the nut 34 so as to extend a predetermined distance beyond one end of the nut in a direction parallel with the direction of travel of the nut. The nut 34 is threaded to travel lengthwise of screw-shaft 37 which is rotatably mounted at its ends in suitable bosses 38 formed on the inner side walls of the casing 13. The lower side of nut 34 is provided with a depending lug 39, preferably forked or bifurcated as shown in Figure 2 to straddle a guide-rod or bar 40 mounted in the lower part of the casing 13; the lug 39 and rod 40 maintaining the nut 34 against rotation and therefore causing the nut to travel lengthwise of screw-shaft 37 when the latter is rotated; the direction of travel depending upon the direction of rotation of screw-shaft 37.

One end of screw-shaft 37 is provided with a gear 41, preferably loosely mounted on the screw-shaft, and this gear meshes with a gear 42 which is secured or made integral with bevel pinion 18 so that gear 42 will rotate with pinion 18. The gear 41, on screw-shaft 37, is shown provided with clutch surfaces at 43 adapted to be engaged by the clutch member 44 which is slidably keyed on the screw-shaft 37.

The front wall of the casing 13 is preferably made in two parts, with the upper part 45 made removable while the lower part 46 is shown formed integral with the

casing. This lower part is shown provided with a lever 47 secured to a shaft 48, the inner end whereof is provided with an eccentric portion or head 49 adapted to extend intermediate of the flanged portions of clutch member 44, so that when the lever 47 is oscillated from a neutral or intermediate position, the eccentric portion or head will force the clutch member 44 either into or out of clutching relation with the clutch surface 43 of gear 41.

With bevel pinions 18 and 19 arranged in mesh with circular gear 23, it is evident that circular gear 23 is caused to be rotated by the selective pinion effected through the positioning of double clutch member 24; that is to say, with the clutch member 24 in mesh with the clutch surface on the hub-portion of pinion 19, power will be transmitted through pinion 19 to circular gear 23 and thus cause the latter to rotate in a given direction, as shown in Figure 1. Pinion 18 being in mesh with gear 23 (but out of clutching relation with clutch member 24) will loosely rotate on shaft 16 and will therefore cause worm-shaft 37 to be rotated through the medium of the gears 41 and 42. With the circular gear 23 being driven by pinion 19, it is evident that gear or pinion 18 will be rotated in opposite direction to the direction of its rotation when it is brought into operative relation with shaft 16 through double clutch member 24 to act as the driving pinion. With this relation of the elements, it is evident that worm-shaft 37 will likewise be rotated in opposite directions depending upon the relation of pinion 18 to the driven shaft 16.

Pivotedly mounted at 50 on bracket 31 is a lever 51 formed to extend along one side of the sleeve member 27; the lower end of the lever 51 being provided with a suitable slot 52 disposed lengthwise of lever 51; the slot being adapted to receive a pin 53 secured to the side of sleeve member 27.

Pivotedly mounted on bracket 31 at a point above the pivotal point 50 and preferably in vertical alignment therewith, namely at the point 54, is a lever 55, the upper end whereof is disposed through a suitable opening 56 in the casing or housing 13 so as to permit manual operation of the lever when occasion requires. A spring 57 has one end secured at 58 to the lever 55, while the opposite end is secured at the point 59 to the lower end of lever 51; said spring maintaining the elements under constant tension tending to draw the free ends of the levers in directions toward each other and therefore toward opposite sides of the "dead centers" of pivotal points 50 and 54 of levers 51 and 55, respectively, with the result that positive movement of the sleeve member 27 and consequently also of the double clutch member 24 is induced. In securing the up-

per end of the tension spring 57 to the movable lever 55, it is apparent that the pull of the spring will alternately be exerted on opposite sides of the pivotal points previously referred to.

The part of lever 51, above its pivotal point 50, is provided with a small lip or lug 60 which is disposed into the slotted or bifurcated end 61 of lever 55. With this 10 construction, movement of either lever 51 or 55 will be transmitted from one to the other, so that movement of sleeve 27, through the action of the pin 36 secured to the arm or lug 33 of traveling member or nut 34, will 15 induce the lower end of lever 51, by reason of its slot and pin connection with sleeve 27, to oscillate about its pivotal point 50 and likewise cause lever 55 to oscillate about its pivotal point 54 through the medium of the 20 lug and slot connection between the two levers. As a result of this construction, it is apparent that the moment lever 51 is oscillated to a point slightly beyond "dead center", that tension spring 57 will induce 25 a further and positive oscillation of lever 51 and therefore a positive shifting of sleeve 27, which will thereby be forced into effective contact with one of the flanges 26 of double clutch member 24 and induce the 30 clutch member to form complete and positive clutching engagement with the selective gear or pinion.

The lever 55 is disposed through the opening or slot 56 in the casing 13, to enable the 35 operator to control the position of the clutch mechanism, especially in situations where the clutch mechanism may have shifted into neutral or intermediate position during an idle moment or in the movement of the machine; while at the same time providing 40 means whereby the clutch element may be thrown out of clutching relation during the operation of the machine should occasion require.

45 In order to prevent any possibility of injury by the insertion of fingers through slot 56, and prevent objects falling through the slot, I have shown lever 55 provided with an arcuate guard 62 adapted to travel beneath the slot 56 and within the casing 13.

Rotation of bevel pinion 18 and therefore also pinion 42, in similar direction with shaft 16 as indicated by the arrow in Figure 1, will induce pinion 41 to rotate in opposite direction and thereby cause nut 34 to travel lengthwise of screw-shaft 37 toward the opposite end until the pin 36, secured in the arm or lug 33 of the nut, has engaged the opposite end of the slot 35 in the 55 lower part of sleeve 27, thereby causing the sleeve to slide lengthwise of double clutch member 34 toward the right in Figure 1 until the sleeve 27 has arrived at a point 60 where lever 51 has been oscillated slightly 65 toward the right of its pivotal point, when

the spring 57 will quickly draw both levers 51 and 55 toward the right in Figure 1 and cause sleeve 27 to positively shift clutch 24 into clutching engagement with the clutch surface of pinion 19. With the pinion 19 70 in operative relation with shaft 16, circular gear 23 will be driven in reverse direction from that induced by pinion 18, which now will be rotated loosely on shaft 16, but in a direction reverse from that previously described. As a result of the reverse rotation of pinion 18 and gear 42, it is evident that screw-shaft 37 will be caused to rotate in a direction opposite to the direction of rotation induced when the pinion 18 acts as the 75 driving pinion for the circular gear 23.

With the difference in size of the gears intermediate of the screw-shaft 37 and pinion 18, the screw-shaft 37 will be caused to rotate at the desired speed relative to the 80 speed of shaft 16, so that by the time traveling member or nut 34 has traveled from one extreme to the other, large circular gear 23 will have been rotated a predetermined number of revolutions, with the result that the 85 cylinder or washing machine agitator will also have been rotated or agitated in a given direction a predetermined number of times before the clutch mechanism has been shifted to cause reverse operation of the cylinder or agitator.

By forming the gear casing 13 with an integral front wall portion 46 as previously described, extending to a point slightly above the horizontal plane of screw-shaft 37, a 100 suitable amount of lubricant or grease may be placed in the lower part of the casing sufficient to immerse the screw-shaft and thereby maintain the screw-shaft and traveling member properly lubricated; while the 105 gear 41 in turn will transmit lubricant to gear 42 and gear 23 will transmit lubricant to the pinions 18 and 19, with the result that all of the running frictional surfaces will be properly lubricated.

110 In forming the shaft housing 11 integral with the shell or casing 13, a very rigid structure is provided and the proper positioning of the respective shaft sections and gears will be ensured.

115 My invention provides driving mechanism which is simple in construction and operation, having the desired or necessary strength and rigidity; which will be positive in its action and at the same time manually controllable; and while I believe the construction shown and described to be the simplest and best embodiment of the invention, certain modifications may be made without, however, departing from the spirit of my invention.

120 What I claim is:—

1. In driving mechanism of the class described, a gear adapted to transmit motion to the device to be operated, a shaft disposed 130

transversely of the gear, a pair of gears loosely mounted on said shaft and arranged in mesh with the first mentioned gear at diametrically opposite points, a double 5 clutch member slidably keyed to the shaft intermediate of the loosely mounted gears and adapted to alternately have clutching engagement with said gears, a member 10 slideable on said clutch member and adapted to control the latter, means adapted to travel in directions lengthwise of said shaft and in controllable relation with said last mentioned member, intermeshing gears intermediate of said means and one of the loosely 15 mounted gears, a pair of pivotally mounted levers having operative relation with each other at points intermediate of their pivotal points, one of said levers being adapted to be manually controlled, while the other lever 20 has operative relation with the second mentioned member, and tension-applying means intermediate of the two levers whereby a positive movement of said levers to opposite sides of their pivotal points will be induced.

25 2. In driving mechanism of the class described, a gear adapted to transmit motion to the device to be operated, a shaft disposed transversely of the gear, a pair of gears loosely mounted on the shaft and arranged 30 in mesh with the first mentioned gear at diametrically opposite points, a double clutch member slidably keyed to the shaft intermediate of the loosely mounted gears and arranged to have clutching engagement 35 with said gears, a screw-shaft disposed parallel with the first mentioned shaft and adapted to be rotated through the medium of one of the loosely mounted gears, a member arranged to travel lengthwise 40 of the screw-shaft, means slidably mounted on the clutch member and controllable by the traveling member on the screw-shaft, said means having yielding operative relation with the clutch member, a spring- 45 controlled pivoted lever having a yielding operative relation with said means whereby the positive operation of said means is controlled, and means whereby the traveling member on the screw-shaft is held 50 against rotation.

3. In driving mechanism of the character described, a gear adapted to transmit motion to the device to be operated, a shaft disposed transversely of the gear, a pair of gears 55 loosely mounted on said shaft in mesh with the first mentioned gear at diametrically opposite points, a double clutch member slidably keyed to the shaft intermediate of the loosely mounted gears and arranged to alternately 60 have clutching engagement with said loosely mounted gears, a screw-shaft disposed parallel with the first mentioned shaft, a member arranged to travel lengthwise of said screw-shaft, gearing intermediate of one 65 of the loosely mounted gears and said screw- shaft whereby the latter is rotated, a member 70 slideable on the double clutch member and having yielding operative relation therewith, means intermediate of the traveling member on the screw-shaft and said third 75 member whereby said third member is controlled through the positioning of the traveling member on the screw-shaft, and spring-controlled means whereby positive movement of the third member is induced and the clutch member thrown into complete clutching engagement with the selective gear of said pair of loosely mounted gears.

4. In driving mechanism of the character 80 described, a one piece casing, one portion whereof receives and provides bearing for the end of a power-transmitting shaft while the other portion is provided with a driven shaft disposed at right angles to the first 85 mentioned shaft, a gear mounted in the second portion of said casing and adapted to transmit motion to the device to be operated, a pair of gears loosely mounted on the driven shaft and arranged in mesh with the first 90 mentioned gear at diametrically opposite points, a double clutch member slidably keyed on the driven shaft intermediate of the loosely mounted gears, a screw-shaft 95 journaled in the second portion of the casing and arranged parallel with the driven shaft, means intermediate of the two shafts whereby the screw-shaft is rotated at a predetermined speed when the driven shaft is rotated, means adapted to travel along said screw-shaft through the rotation of the latter, a member slideable on the clutch member and having yielding operative relation therewith, said last mentioned member being arranged in yielding operative relation 100 with the last means, and a spring controlled lever arranged in operative relation with said last member whereby the latter is given positive movement and the clutch member thereby shifted into positive relation with the selective gear of said pair of gears.

5. Driving mechanism of the character 105 described, comprising a gear adapted to transmit motion to the device to be operated, a shaft disposed transversely of the gear, a 110 pair of gears loosely mounted on said shaft and arranged in mesh with the first gear at diametrically opposite points, a double clutch slidably keyed on the shaft intermediate of the loosely mounted gears, 115 adapted to alternately have clutching engagement with said pair of gears, means adapted to travel in directions lengthwise of said shaft and operable through rotation of one of said loosely mounted gears, a member 120 arranged in yielding operative relation with said means and controlled thereby, said member having operative relation with the double clutch, and spring-controlled means 125 oscillatingly mounted so as to control the 130

- member when the means has been shifted to opposite sides of its pivotal point, whereby positive shifting of the double clutch is obtained.
5. 6. Driving mechanism of the character described, comprising a gear adapted to transmit motion to the device to be operated, a shaft disposed transversely of the gear, a pair of gears loosely mounted on said shaft and arranged in mesh with the first mentioned gear at diametrically opposite points, a double clutch slidably keyed to the shaft intermediate of the loosely mounted gears, adapted to alternately have clutching engagement with said pair of gears, a member 10 slidable on said clutch and adapted to control the latter, means whereby said member is held against rotation, means adapted to travel in directions lengthwise of the shaft and arranged in controllable relation with said slidable member, intermeshing gears intermediate of said means and one of the loosely mounted gears, a spring-controlled member oscillatingly mounted above said 15 slidable member and in operative relation therewith for inducing final positive shifting of the slidable member and said clutch, and manually operable means for controlling said spring-controlled member.
- 20 7. Driving mechanism of the character described, comprising a gear adapted to transmit motion to the device to be operated, a shaft disposed transversely of the gear, a pair of gears loosely mounted on said shaft and arranged in mesh with the first mentioned gear at diametrically opposite points, a double clutch slidably keyed to the shaft intermediate of the loosely mounted gears, adapted to alternately have clutching engagement with said pair of gears, a member 25 mounted on said clutch in operative relation therewith adapted to control the clutch, means whereby said member is held against rotation, a rotatable shaft controlled by one of said pair of loosely 30 mounted gears, adapted to rotate in opposite directions, an oppositely movable member, controlled through rotation of said last mentioned shaft, having slot and pin connection with said first mentioned member, adapted to move said first member into clutch-shifting position, and a spring-controlled member oscillatingly mounted above said first member and in operative relation 35 therewith whereby the latter is given final movement to induce positive shifting of said clutch into operative relation with the selective gear of said pair of gears.
- 40 8. In a driving mechanism of the character described, a housing, one portion whereof constitutes a gear-casing in which the ends of a drive-shaft and a driven-shaft are rotatably mounted, while the other portion provides a casing for the motion-imparting mechanism which comprises a circular gear disposed parallel with the driven-shaft, a pair of gears loosely mounted on the driven-shaft and arranged in mesh with the circular gear at diametrically opposite points, a double clutch slidably keyed on 45 said shaft intermediate of said pair of gears and adapted to alternately move into clutching engagement therewith, a worm shaft rotatably mounted in said second portion of the housing, parallel with the driven shaft and arranged to be rotated through the medium of one of said loosely mounted gears, a member threaded on said worm-shaft, means whereby said member is held against rotation and made to travel lengthwise of the worm shaft, a member slidably mounted on the double clutch, controllable by the member on the worm shaft, said second mentioned member having yielding operative relation with said double clutch, 50 a pair of levers oscillatingly mounted in the second portion of the housing above said second mentioned member and arranged in operative relation with each other, one of said levers having yielding operative relation with the double clutch, and a spring connected to said levers at opposite sides of their pivotal points, adapted to shift said levers beyond "dead center" when the second mentioned member has been shifted a predetermined extent, whereby the clutch is shifted into positive gear-engaging position.
- 55 9. Driving mechanism of the character described, comprising a gear adapted to transmit motion to the device to be operated, a shaft disposed transversely of the gear, a pair of gears loosely mounted on said shaft and arranged in mesh with the first gear at diametrically opposite points, a double clutch slidably keyed on the shaft intermediate of the loosely mounted gears and adapted to alternately have clutching engagement with said pair of gears, a worm-shaft disposed parallel with said first shaft, 60 gears intermediate of said worm-shaft and one of the pair of gears whereby the worm-shaft is rotated, a member threaded on said worm-shaft, means whereby said member is held against rotation and caused to ride lengthwise of said worm-shaft, a member 65 mounted on said double clutch and having slot and pin connection with the member threaded on the worm-shaft, means whereby said second member is held against rotation and guided in its movement, a pair of levers pivotally connected on said last means, with the pivotal points of said levers arranged in vertical alignment and the adjacent ends of the levers in operative relation with one another, and tension-applying means secured to both levers whereby the latter are positively oscillated toward opposite sides of their pivotal points when said levers have been moved a predetermined extent, one of said levers being adapted to control the final 70
- 75 80 85 90 95 100 105 110 115 120 125 130

6
positioning of said second mentioned member, while the second lever is manually operable.

10. Driving mechanism of the character 5 described, comprising a housing, a circular gear mounted in one wall of said housing, a shaft disposed through said housing transversely of said gear, a pair of gears loosely mounted on the shaft and in mesh at diametrically opposite points with said first gear, a double clutch slidably keyed on said shaft intermediate of the pair of loosely mounted gears and adapted alternately to have clutching engagement with said pair 10 of gears, a worm-shaft rotatably mounted in said housing parallel with said first shaft, gears intermediate of the worm-shaft and one of said loosely mounted gears for imparting rotation to the worm-shaft in opposite 15 directions, a member threaded on said worm-shaft and provided with a projection or arm disposed parallel with the worm-shaft, means with which said member has 20 slidable engagement whereby rotation of said member on the worm-shaft is prevented, 25

a sleeve slidable on said double clutch and having slot and pin connection with the projection or arm of the member threaded on the worm-shaft, a bracket mounted in said housing above said first mentioned shaft 30 and provided with a depending projection having sliding relation with said sleeve, a pair of levers pivoted on said bracket at points in vertical alignment to permit said levers to oscillate, the adjacent ends of said 35 levers having operative relation with one another, the lower lever being adapted to control said sleeve while the upper lever is disposed through the housing to permit manual operation, and a spring secured to both 40 levers at points above and below their respective pivotal points so as to induce positive oscillation of the levers past their dead centers and thereby force said sleeve into clutch-actuating position.
